[57] CLAIM

The ornamental design for a tower for personal computers, as shown and described.

DESCRIPTION

FIG. 1 is a front elevational view of a tower for personal computers showing our new design;

FIG. 2 is a front elevational view of a second embodiment thereof;

FIG. 3 is a front elevational view of a third embodiment thereof;

FIG. 4 is a front elevational view of a fourth embodiment thereof;

FIG. 5 is a left side elevational view of the fourth embodiment;

FIG. 6 is a right side elevational view of the fourth embodiment;

FIG. 7 is a top plan view of the fourth embodiment;

FIG. 8 is a bottom plan view of the fourth embodiment;

FIG. 9 is a rear elevational view of the fourth embodiment;

FIG. 10 is a perspective view of the fourth embodiment;

FIG. 11 is a left side elevational view of the first embodiment, with the undisclosed right side elevational view being identical in appearance thereto;

FIG. 12 is a left side elevational view of the second embodiment, with the undisclosed right side elevational view being identical in appearance thereto; and,

FIG. 13 is a left side elevational view of the third embodiment, with the undisclosed right side elevational view being identical in appearance thereto.

The undisclosed top, bottom, and rear views of embodiments 1-3 are identical in appearance to those shown in the fourth embodiment.
